Specification for Design.

Patented June 11, 1918.

Application filed August 22, 1917. Serial No. 187,546. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for Furniture, Casket, Interior, or Exterior Decoration, of which the following is a specification, reference being had to the accompanying drawing, forming a part hereof.

The drawing is a front elevation or face view illustrating my design.

This design consists of oppositely and symmetrically arranged horns of plenty containing fruits, flowers, leaves, buds, etc., and having their inner end portions curving upwardly and touching each other and their

extreme ends diverging outwardly and terminating in scrolls, a conventional husk depending from the horns at the points they touch together and a ribbon encircling the horns where they come together, the end portions of the ribbon extending laterally toward the top end portions of the horns.

I claim:

The ornamental design for furniture, casket, interior or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
